UNITED STATES PATENT OFFICE.

CHARLES S. SMITH, OF CHICAGO, ILLINOIS.

SCREEN.

1,310,305.

Specification of Letters Patent. Patented July 15, 1919.

Application filed November 11, 1918. Serial No. 261,951.

To all whom it may concern:

Be it known that I, CHARLES S. SMITH, a citizen of the United States, residing at Chicago, in the county of Cook and State of Illinois, have invented certain new and useful Improvements in Screens, of which the following is a specification.

This invention relates to screens of the kind that is used adjacent windows. More particularly, it is of the roller type; that is, it is of the type that is mounted upon a spring roller so as to wind thereupon when not in use. The screen is so arranged with respect to a window sash that it automatically unrolls as the sash is opened, and rolls up again as the sash is closed.

With a view to the production of a screen of this kind, I have aimed to device a structure that is simple, compact, and relatively inexpensive. Further, it has been an object of this invention that the screen should be easily secured in operative position, and just as easily removed therefrom. A connection between the screen and sash has, furthermore, been arranged such that it is difficult, if not impossible, to remove the screen while the window remains open, but with complete closing of the window its removal may be readily accomplished.

In the description to follow, other objects, purposes, and uses of my invention will become apparent. A structure in which is represented the improved features of my screen is shown in detail in the accompanying drawings wherein—

Figure 1 is an elevation of a window frame in which is a sliding sash shown partly open, and the present screen partly unrolled;

Fig. 2 is a transverse section, enlarged, through the screen, together with the adjacent parts of the window, the screen in this view being partly unrolled as in Fig. 1;

Fig. 3 is a view similar to Fig. 2, except that the screen is shown as completely rolled up, the sash in this view being completely closed;

Fig. 4 is a horizontal section through the case taken on line 4—4 of Fig. 3; and

Fig. 5 is a detail in elevation of the hook secured to the sash which makes connection with the screen.

It is desirable that the present screen should be adequately protected, and for this purpose I have provided an inclosing case consisting of a bottom 10, a back 11 usually

at right angles thereto, and a combined front and top piece 12 suitably rounded or curved as shown in Figs. 2 and 3. Ends 13 are also provided in which are mounted 60 trunnions of a roller 14 which may be hollow or otherwise, and which is preferably operated against the tension of a coiled spring 15. Formed in the bottom of the case are key-hole slots 16, as many as necessary, through which extend screws 17 secured to the sill of the window frame, to lock the case in operative position adjacent the sash. As this form of connection is well known, further description thereof is unnecessary.

Arranged upon the roller and within the case is a screen 18 of any suitable material, and by preference sufficiently flexible to wind upon the roller as many times as necessary. The free edge of the screen is reinforced with a strip 19 suitably fastened in place and bent over and upon itself in the form of a hook to provide a channel 20. In order that the screen may unroll and roll up 80 again upon the roller within the case, I have provided a slit 21 lengthwise thereof in the top piece 12 adjacent the back 11, and as the screen is wound upon the roller, its free edge approaches the upper edge of the back 11 85 until finally the reinforcing strip hooks thereon as shown in Fig. 3.

The construction of the screen having been described in detail, I will now explain its coöperation with the sash. The means 90 for accomplishing this is exceedingly simple, consisting of one or more hooks 22 (a single hook only has been illustrated as one will commonly suffice) secured to the lower rail of the sash and so shaped as to present an 95 upwardly extending tongue which is offset or otherwise formed to stand out slightly from the sash. When the window is closed, as shown in Fig. 3, this tongue will lie below the reinforced edge of the screen which, 100 at such time, overlies the upper edge of the back 11; but with raising of the sash, this hook 22 enters the channel 20 formed in the strip 19. By preference a slit 23 is formed in the bend of the strip such that the tongue 105 of the hook 22 may enter therein (see Fig. 2) to correctly engage with the screen. It will be manifest, of course, that the parts so formed connect the screen to the sash, so that the screen will be unwound and rise 110 with the sash to occupy the space in the window frame that is vacated by the sash as it

is moved upwardly. Conversely, the screen is lowered and rewound within its protecting case as the sash is lowered. It may be found expedient to arrange upon the inside 5 stops which guide the sash in its movements, small strips 24, as shown, which overlie the side edges of the screen when it is raised, thus closing what otherwise would be open spaces, rather narrow to be sure, but undesirable nevertheless.

10 I have shown and described the present screen in relation to the lower sash of a window; it is obvious, however, that it may be used in connection with the upper sash as 15 well by making the proper reversals in position. Other uses may also be found for a screen constructed in accordance with my invention, and these, as well as any modifications or changes in detail which embody my 20 improvements as defined in the appended claims, I desire to include within the scope of this patent.

I claim:

1. In combination with a window sill and 25 a sliding sash, a casing mounted on the sill, a spring roller rotatably mounted in the casing and carrying a flexible screen, the front edge of the casing normally resting in proximity to and extending parallel to the sash, 30 a slit in the top of the casing, adjacent the front edge thereof, through which the screen extends, a downwardly facing channeled strip carried by the free edge of the screen and provided with a flange extending downwardly between the casing and sash and adapted to engage and overhang the top of the front edge of the casing, when the screen is in its inoperative position, and means on the sliding sash for engaging said strip 35 when the sash is raised, substantially as described.

2. In combination with a window sill and

a sliding sash, a casing mounted on the sill, a spring roller rotatably mounted in the casing and carrying a flexible screen, the 45 front edge of the casing normally resting in proximity to and extending parallel to the sash, a slit in the top of the casing, adjacent the front edge thereof, through which the screen extends, a downwardly facing channeled strip carried by the free edge of the screen and provided with a flange extending downwardly between the casing and sash and adapted to engage and overhang the top of the front edge of the casing, when 50 the screen is in its inoperative position, and means on the sliding sash for engaging said strip when the sash is raised, and for releasing said clip when the window is closed and the clip contacts the top of the casing, 55 substantially as described.

3. In combination with a window sill and a sliding sash, a casing mounted on the sill, a spring roller rotatably mounted in the casing and carrying a flexible screen, the 60 front edge of the casing normally resting in proximity to and extending parallel to the sash, a slit in the top of the casing, adjacent the front edge thereof, through which the screen extends, a downwardly facing 65 channeled strip carried by the free edge of the screen and provided with a flange extending downwardly between the casing and sash and adapted to engage and overhang the top of the front edge of the casing, when 70 the screen is in its inoperative position, an aperture in the top of the strip, and a hook carried by the sliding sash and adapted to enter said aperture and raise the screen when the sash is elevated, substantially as 75 described.

CHARLES S. SMITH.
